UNITED STATES PATENT OFFICE

WARREN NOBLE, OF DETROIT, MICHIGAN

POPPET VALVE

No Drawing.

Application filed September 15, 1927. Serial No. 219,814.

This invention relates to the poppet valves of internal combustion engines in connection with which considerable thought and experiment has been exercised in the past by valve 5 and engine designers with a view to perfecting a valve which would satisfactorily withstand the temperatures to which the valves and especially the exhaust valves of internal combustion engines are exposed in use.

10 Among the means employed or suggested have been exhaust valves with special means for cooling the stems such as the flow of heat conducting agent therethrough with a view to disperse heat from the head of the valve 15 through the stem thereof and on the other hand attempt to meet the problem with more or less success have involved the use of special heat resisting alloys from the heads of the valves calculated to withstand high temperatures 20 in view of the difficulty of getting rid of this heat quickly.

The present invention differs materially from this latter attempted solution of the problem in that it provides a valve head of a 25 metallic composition or alloy which is characterized by its heat conducting properties as distinguished from purely heat resisting properties whereby it lends itself to rapid dissipation of its heat radially from the valve 30 head to the seat of the valve and also through the stem thereof if heat dissipation in this direction be also desirable.

More particularly the said invention contemplates of the use of silver, a metal having 35 a very high co-efficient of heat, said silver being alloyed with a suitable metal or metals to give it the required strength and wearing properties required in the head of a poppet valve adapted to use in an internal combustion engine. In carrying the invention to effect I prefer to use a composition including magnesium 10 per cent and silver 90 per cent which may have a tensile strength in excess of 40,000 pounds and a Brinell hardness 40 ranging above 105. I may use as an alloy for a poppet valve head a composition including for example aluminum 15 per cent and silver 85 per cent, such a composition having a tensile strength ranging above 50 40,000 pounds and Brinell hardness ranging

above 140. Both of these compositions are homogeneous and lend themselves well to finishing by grinding and lapping of seating surfaces free from pits and open structure.

Silver has very high co-efficient of heat conductance, and alloying with aluminum or magnesium within reasonable limits does not reduce the conductivity to such an extent that its advantage is lost, so that the high heat conductivity of valve heads made from such composition is a typical characteristic. 55

Poppet valves depend mainly for their heat dissipation on the transfer of heat therefrom to the valve seats and incidentally through the valve seats to metal or cylinder 60 heads but it is obvious that this dissipation is facilitated by the use of a metal or alloy in the head which has this special characteristic and that therefore as a result of the heat dissipation so promoted, the general temperature 65 of the valve head is lower than would otherwise be the case and that heat resisting nature of the head is as a consequence a matter of less importance. 70

Although the use of such a composition is 75 described simply in connection with the head of a valve it may be also partly or entirely extended to the stem of the valve if so desired where conditions of the engine designed are 80 such that some of the heat may be dissipated through the stem. 85

A valve in which a silver alloy as suggested is used for the purposes of obtaining high heat conductivity in the head thereof may be very advantageously used with the 85 heat conductive valve seat described in my copending application Serial No. 219,813, filed Sept. 15, 1927, an arrangement which still further increases the facility with which heat may pass from the valve to the metal of 90 the cylinder head of the engine. 95

What I claim is:—

1. In a poppet valve for internal combustion engines, a head composed of a binary alloy of silver and a metallic hardening agent 95 wherein the silver predominates to an extent wherein its inherent co-efficient of heat conductivity is characteristic of the alloy, and wherein the hardening agent imparts wear resisting properties to the head. 100

2. In a poppet valve for internal combustion engines, a head composed of a magnesium silver alloy in which the silver predominates to an extent wherein its inherent co-efficient of heat conductivity is characteristic of the alloy, and wherein the magnesium supplies to the alloy great wear resisting properties.
3. In a poppet valve for internal combustion engines, a head composed of a magnesium silver alloy wherein the approximate proportions of the elements are 10 per cent magnesium and 90 per cent silver.
4. A poppet valve for internal combustion engines, composed of a binary alloy of silver and a metallic hardening agent wherein the silver predominates to an extent wherein its inherent co-efficient of heat conductivity is characteristic of the alloy, and wherein said hardening agent imparts wear resisting qualities to the head and stem of said valve.
5. A poppet valve for internal combustion engines, composed of a magnesium silver alloy in which the silver predominates to an extent wherein its inherent co-efficient of heat conductivity is characteristic of the alloy, and wherein the magnesium imparts wear resisting properties thereto.
6. A poppet valve for internal combustion engines, composed of a magnesium silver alloy wherein the approximate proportions of the elements are 10 per cent magnesium and 90 per cent silver, and with a sufficient quantity of magnesium included therein to impart wear resisting properties to said valves.

In testimony whereof I affix my signature.
WARREN NOBLE.
